WATER SEAL FOR LOG BARKING DRUMS

Gordon F. McClay, Sherbrooke, Quebec, Canada,
assignor to Ingersoll-Rand Company, New York,
N. Y., a corporation of New Jersey

Application May 15, 1951, Serial No. 226,375

6 Claims. (Cl. 144—208)

1

This invention relates to a sealing device for log barking drums and more particularly to a water seal for the supports of a log barking drum mounted in a washing tank.

Log barking drums of the type to which this invention relates are generally huge open-ended drums supported by trunnions in which run tires mounted on the circumference of the drum. Logs, stripped of branches, are dumped into the drum and the drum is rotated so as to cause the logs to tumble about within the drum thereby rubbing the bark free of the log. The freed bark falls through openings in the side of the drum and is washed or otherwise carried free of the drum.

Under certain circumstances it is desirable to mount the drum within a washing tank—a large wooden or concrete tank partially filled with water—to aid not only in loosening the bark from the log but also to wash the bark free of the drum. Under such circumstances practice has shown that it is extremely difficult to properly lubricate the trunnions and to keep the bearing surfaces of the trunnions free of dirt and grime.

It is, accordingly, one object of this invention to provide a seal for the supports of a drum mounted in a washing tank to prevent contact of the washing fluid with the supports.

Another object of this invention is to provide substantially water tight compartments in the washing tank for the drum supports.

Further objects of this invention will become apparent in the following specification and drawings in which,

Figure 1 is a longitudinal view, partly in section, of an end portion of a log barking drum provided with a water seal for the drum supports.

Fig. 2 is an end view of the drum shown in Fig. 1 and taken along the line 2—2 looking in the direction of the arrows.

Fig. 3 is an end view of a log barking drum provided with a modified form of the invention shown in Figure 1.

Fig. 4 is a transverse view taken through Fig. 3 along the lines 4—4 looking in the direction of the arrows, and shows the turning shield for positioning the fluid seal.

Fig. 5, a detail of Fig. 3, shows a side view of the flexible sealing members mounted on the drum, and shows their position when the members are above the surface of the water in the tank.

Fig. 6 is a transverse view taken through Fig. 5

2

3 along the line 6—6 and looking in the direction of the arrows, and

Fig. 7 is a transverse view taken through Fig. 4 along the line 7—7 and looking in the direction of the arrows.

Referring to the drawings, and more particularly to Figures 1 and 2, the number 10 indicates, generally, a log barking drum rotatably mounted on supports 12 in a washing tank 11. The drum 10, shown by way of illustration, is constructed of longitudinally disposed staves 13 on which are mounted hoops 14 spaced relative to each other along the length of the staves 13. The hoops are of sufficient width to provide sealing surfaces on their outer periphery to cooperate with sealing elements 20 described in detail hereinafter. Mounted on the hoop 14 adjacent the end of the drum 10 is an annular track, or tire, 15 which rides in the supports 12. The supports 12 are here illustrated in the form of trunnions 12, one set of trunnions being mounted on each side of the drum 10. There is, of course, a similar set of supports and a tire at the opposite end of the drum 10 (not shown).

Rotation is imparted to the drum 10 by means of a girth gear 16 mounted on an intermediate hoop 14 and having a driving connection with a motor (not shown).

In the preferred form of the invention, the seal for sealing the trunnions, or supports, 12 from the washing fluid in the tank 11, comprises wall means, the two walls 17, extending upwardly from the bottom of the tank 11, and transversely and in parallelism across the tank 11 on the opposite sides of the trunnions 12. The upper end, or edge, surfaces 18 of the walls 17 are semi-circular in shape to conform with the circumference of the tank 11. The wall means 17 include rigid flanges 19 secured to the edge portions of the walls 17. The flanges 19 are also semi-circular in shape having their upper edge surfaces conforming to, but spaced from, the periphery of the tank 11.

The flanges 19 cooperate with a flexible flange, or sealing member 20, to prevent the leakage of water from the tank into the space between the walls 17 and into contact with the trunnions 12. In furtherance to this end the sealing member 20 is a flat, semi-circular strip of flexible material, such as rubber, secured at its marginal portion to the flange 19 by means of bolts 28 and a binding strip 29 (see Figs. 1 and 2). The width of the strip of sealing material 20 is greater than the distance between the periphery of the drum 10 and the free edge of

55

3

the flange 19. Due to this construction, the seal 20, in its operative position, is flexed so that

4

ing elements mounted on said walls and held in sealing contact with said sealing surfaces to pre-
